United States Patent

Des. 234,950
Patented Apr. 22, 1975

234,950

AUDIO VISUAL TEACHING UNIT

Robert E. Aumann, Rte. 1, Iron Ridge, Wis. 53035

Filed June 8, 1973, Ser. No. 368,337

Term of patent 14 years

Int. Cl. D14—01

U.S. Cl. D19—60

Fig. 1

Fig. 2

FIG. 1 is a front elevational view of an audio visual teaching unit embodying my new design.

FIG. 2 is a bottom elevational view.

The undisclosed side, rear and top surfaces of the unit are plain and unornamented, and the rear and top surfaces of the handle member, which is of conventional thickness, are planar.

I claim:

The ornamental design for an audio visual teaching unit, as shown and described.
